PASSENGER OPERATED SWING DEVICE

Walter Liebrecht, New York, N. Y.

Application March 29, 1941, Serial No. 385,917

13 Claims. (Cl. 272—57)

This invention relates to amusement devices, and especially those adapted for use at amusement parks, carnivals and the like, and with which a number of persons may engage in competitive activity.

The primary object of the invention is to provide a device of the character mentioned wherein a plurality of persons are each carried in a swinging conveyance toward a support upon which a number of successively-operated control elements are mounted, said elements controlling the operation of suitable signal devices so that the sequence of operation of the control elements will be indicated by the signal devices and the more expert of the persons operating his conveyance will operate the requisite number of control elements more speedily than the other persons and be thus adjudged the winner. Since the device involves physical effort and skill, it will be found interesting, exhilarating and amusing.

In the accompanying drawing, constituting a part hereof, and in which like reference characters indicate like parts,

Fig. 1 is a diagrammatic view showing the electrical connections and elements for operating the device, embodying a rotary switch, the parts thereof being in detached positions for clearness;

Fig. 2 is a perspective view of the device showing the relative positions of the swings and co-operating wall;

Fig. 3 is a front view of a slightly modified form of the device;

Fig. 4 is a diagrammatic side view showing the relationship of swing to wall, and

Fig. 5 is a vertical cross-sectional view of one of the pedals of Fig. 2.

The device as shown in Fig. 2 consists of a plurality of swings, each intended to receive a passenger and be swung in the conventional way by the physical efforts of the passenger, toward a support carrying a plurality of foot-operated switches arranged one above the other. These switches are adapted to be successively operated by the foot of the passenger, in a predetermined sequence, as the swing carrying the passenger travels in its arc over the support. Since several swings are provided, the object sought by each passenger is to outstrip his companions by being the first to operate in sequence all of the switches in the group over which his swing traverses. Each switch is connected to a signal such as a lamp, the lamps being illuminated and remaining so during operation of the device so that each contestant may by watching the lamps, note his own progress and that of the other contestants.

The end or final switch in each group is connected to a "winning" audible and visible signal, and the first contestant to operate the last switch in his group is adjudged the winner of the contest. Means is provided by which all other "winning" signals are rendered ineffective when one of the last switches is operated.

In the device of Fig. 3, substantially the same arrangement as that of Fig. 2 is employed, except that the foot-operated switches are arranged in a row extending transversely of the direction of movement of the swings. The lamps are similarly arranged, and they are placed to simulate a musical score.

With reference to the structure of Fig. 2, a plurality of swings 1 and 2 are suspended in the conventional manner upon the bar 4. The swings are disposed in side-by-side relation and in a single line and as many of these swings may be employed as desired, only two being shown to simplify illustration. Each swing is operable independently of the others, and preferably by the physical efforts of its occupant, so that the individual effort and skill of the several occupants determines the winner.

Located in front of the swings is a curved or inclined supporting surface or wall 5. The arc of the wall is, as shown in Fig. 4, based on a center different from that of swing 1, so that the arc 1' of movement of the swing approaches the wall at the highest point of the movement. This tends to promote the safety of the players. The wall 5 may be divided into separate and independent sections, one for each of the swings. This wall or support may be constructed of any suitable material and may be supported by the framework 6. When the wall is of separate sections, they may be resiliently mounted to avoid possible injury to the occupants of the swings in the event of an accident or in the event of extraordinary foot pressure being exerted by one or the other occupants on the support.

Located in front of each of the swings, and so mounted in the wall or support 5 as to be substantially flush with the curved surface thereof, is a plurality of pedals indicated at 8 to 13, inclusive, these pedals being hinged or otherwise resiliently mounted in the support so that when the swing moves over the support, the pedals can be easily reached by a foot or feet of the occupant of the swing and successively depressed.

The electrical system shown in Fig. 1 consists essentially of a series of pedal operated switches and a step-by-step rotary switch, a series of lamps, audible and/or visible winning signals,

and relays, all being so interconnected as to provide the desired functions with the proper timing. Each pedal operates a switch of the push-button type, whereby a single foot-thrust on a pedal will close a switch to light a lamp. Pedal 8 will thus close switch 8a, while pedal 9 will operate switch 9a, pedal 10 operating switch 10a, pedal 11 operating switch 11a, pedal 12 operating switch 12a and pedal 13 operating switch 13a. One contact of all of the switches is connected to one side 35 of the power line, designated as negative side for convenience in illustration, the other contact 36 of each switch connecting to one of a series of contacts indicated at 8b to 13b inclusive. Circuit between these contacts and the positive side of the power line is closed by a contact finger 15, secured on a shaft 16, and adapted to be moved with a step-by-step movement from one contact to the next, or for example, from the contact 8b to contact 9b and thence to contact 10b and so on, until the last contact, indicated at 13b is reached. The contact finger 15 is shifted from one of the contacts to the next by the successive operation of the pedals 8 to 13 inclusive in proper sequence.

Secured upon the shaft 16, also, and movable therewith is an arcuate contactor or wiper 17 connected by the wire 18 to the negative side 35 of the power line. Said contactor 17 is adapted to close circuit with a bank of contacts designated at 8c to 13c inclusive, each of the contacts 8c to 13c being connected by wiring to a lamp, said lamps being designated as 8d to 13d inclusive. The lamps also have connections, as usual, to the positive side 23 of the power line. The lamps 8d to 13d are each arranged, in the embodiment of the invention shown in Fig. 2, alongside of the pedal which causes the lamp to be illuminated, and each lamp when illuminated, will remain so, so that each contestant may, by watching the lamps, ascertain his progress and that of his fellow contestants.

Fig. 5 shows the mounting of the pedals. A coil spring 40 is mounted on rod 41 having a head 42 secured to pedal 8. The opposite end of rod 41 has a head 43 held against the outer face of support 5, the rod being adapted to move freely in opening 44. Pedal 8 has contact member 8d cooperating with contact member 36 on support 5, constituting a switch.

In its inoperative or initial position, the device is as shown in Fig. 1 with switches 8a to 13a biased in open position and contacts 22, 28 and 30 biased in closed position. When the occupant of the swing situated in front of a group of pedals, depresses the pedal 8, switch 8a will be closed, and since the finger 15 is at this time located on contact 8b, current will flow through the contact finger 15 and through wire 19 to energize driver magnet 20, forming part of the step-by-step switch of conventional form that includes the shaft 16 and contact members 15 and 17 and contacts 8b to 13b, and contacts 8c to 13c. Driver magnet 20 will then rotate shaft 16 for one step to cause finger 15 to move to the second contact, or that indicated at 9b and remain in contact therewith. Simultaneously, the arcuate contactor 17 will be moved to engage contact 8c and the signal lamp designated at 8d will be illuminated. Current flowing through wire 19 will also energize a relay 21 of the delayed-action type, and this relay opens its movable contact 22, holding the same open for a short period, say one-fourth of a second, stopping the movement of arm 17, so that only one

of the pedals can be operated at a time and in proper sequence to cause the successive lamps to be illuminated. After a short interval, contacts 22 will close, by suitable means, such as a plunger to retard the return movement of contact 22, and when the next pedal, or that indicated at 9 is depressed, lamp 9d will be illuminated. The successive illumination of the lamps 10d to 13d will take place in the proper sequence by the successive depression of the pedals until the last pedal, or that indicated at 13, is depressed, the operation of which will set in operation the winning signal, which can consist of a lamp or illuminated sign, diagrammatically indicated at 24. The so-called "winning signal" can also include or be an audible signal, such as a phonograph 25 which can be set in operation to play a record when the last pedal in any one of the groups is depressed.

The last contact 13c is connected by wire 26 to the lamp signal 24 and phonograph 25. Connected in parallel to signals 24 and 25 and the last contact 13c is a relay indicated at 27 which is energized when pedal 13 is depressed, and it is so connected in to the circuit of the adjacent switch groups that the last pedal in any of the other groups when then depressed will be ineffective to operate the winning signals for such groups. For example, if it is assumed that the pedal 13 for swing 1 is the first of the final or last pedals in the two groups shown, to be depressed, the winning signals 24 and 25 will be set in operation. At the same time, relay 27 will be energized and the same will open relay contacts 28 in the circuit controlled by pedals operated from swing 2 so that the occupant of swing 2 can thereafter depress his last pedal 13 without his winning signals being set in operation. Should the occupant of swing 2 be the first to depress his pedal 13, the relay 29 controlled by the pedal 13 for the group operated by swing 2, will open switch 30 and then the occupant of swing 1 will be unable to operate his winning signal by depression of his pedal 13.

While I have, in order to simplify the description and operation of the device, shown only two swings and the mechanism operated by the occupants thereof, it will be understood that the number of swings may be increased to an appreciable extent. When more than two swings are used, the relays employed as at 27 and 29 will be arranged to disconnect electrically the winning signals of all of the remaining swings after any one swing occupant has depressed his last pedal.

In the structure of Fig. 2, the pedals 8 to 13 inclusive are arranged for successive operation in a direction co-extensive with the arc in which the swing travels, while in Fig. 3 the pedals are constructed to resemble piano keys and to be operated from left to right or in a direction transverse to the direction of swing travel, the signal lamps 8d to 13d being arranged to resemble musical notes. Other attractive and interesting variations may be employed as will be readily apparent to those skilled in the art.

In the operation of the device, the occupants of the swings proceed to propel the swings, preferably but not wholly necessarily, by their own physical efforts. When pedal 8 is depressed by a swing occupant, as his swing carries him in position to reach this pedal with his foot, lamp 8d will be illuminated and will remain illuminated. On his next forward movement of the swing, he will by increasing his efforts, be en-

abled to reach pedal 9, which upon being depressed, will illuminate lamp 9d. The successive depression of the pedals continues until the last pedal, or that indicated at 13, is reached, whereupon the first of the swing occupants to reach and depress that pedal in his switch group will illuminate his winning signal 24 and sound his audible winning signal 25. The depression of the first pedal 13 in any group will, by operation of the relays 21 or 29, disconnect all other winning signals 24 and 25 and prevent anyone but the winner from operating his winning signals.

Contacts 28 and 30 may be connected so as to disconnect driver magnet 20 or wiper 17, by opening wire 19 or 18, respectively. After each game is finished, means are provided for placing all the elements in starting position.

While I have shown and described several embodiments of the invention, it is obvious that the same may be modified in many ways without departing from the spirit of the invention. Although in the specification I have referred to a wall, it need not be solidly constructed but it may consist of any suitable support for the pedals. The wall or walls and the pedals may be made of or be covered with shock absorbing materials. The lamps in Fig. 1 are shown staggered to correspond with the locations of the musical notes as placed on Fig. 3, but other arrangements to suit the circumstances may be used. In place of the step-by-step switch shown in Fig. 1, any other switch of this type may be substituted, as such switches are well known. Where a phonograph record is operated as a winning signal, a different record for each of the units of the device may be provided and a single operating mechanism be provided for all the units so that only one mechanism is required.

In view of the above, the invention is to be broadly construed and to be limited only by the character of the claims appended hereto.

What I claim is:

1. An amusement device comprising, a plurality of independently operated swingingly mounted conveyances, each of said conveyances holding a passenger and mounted for propulsion by the physical effort of only the passenger occupying the same, a support over which the several conveyances move when propelled by their respective passengers, a group of control devices on said support disposed in the path of movement of each conveyance and adapted for operation by the passenger as the conveyance moves adjacent to the control devices, and means connected to said control devices and to a signal device and by which said signal device is operated when all of the control devices in a group have been successively operated by the passenger in the conveyance movable adjacent to said group.

2. An amusement device comprising, a plurality of independently operated swinging conveyances, each of said conveyances holding a passenger and mounted for propulsion by the physical effort of only the passenger occupying the same, a support over which the several conveyances are swung, a group of control devices in the path of movement of each conveyance and adapted for operation by the passenger as the conveyance swings over them, signal devices and means connected to said control devices and to the signal devices for successively operating a signal device when each one of the control de-

vices is operated and for operating another signal device when all of the control devices in a group have been operated.

3. An amusement device comprising, a plurality of independently operated swings, a support over which each of the swings is swung by the physical efforts of only the passenger occupying the same, a group of switches on the support and disposed in the path of movement of each of the swings, and arranged for operation by the physical effort of the passenger of each swing, an electric signal connected to each switch and arranged for actuation when each switch is operated, and another signal arranged for actuation when the last switch in a group is operated.

4. An amusement device comprising, a plurality of independently operated swings, a support over which each of the swings is swung by the physical efforts of only the passenger occupying the same, a group of switches on the support adjacent to each swing and in position to be operated by the foot of the passenger thereof as the swing moves over the support, signal devices, and an electrical circuit connecting the signal devices and the switches and by which the signal devices for each group of switches will be successively operated with the switches in said group are successively operated by the passenger in the swing moving over said group, and other signal devices operative when the last switch in any one of the groups is first operated.

5. An amusement device comprising a plurality of independently operated swings, a support over which each of the swings is swung, a group of switches on the support and disposed in the path of movement of each of the swings and arranged for operation by the foot of the passenger in the swing, an electrically controlled signal connected to each switch and adapted for operation when each switch is operated, means for preventing operation of the signals in any one group unless the switches for said group are operated in sequence, and an additional main signal for each group, said main signal being operated when and if the last switch in any group is the first one of the last switches in all of the groups to be operated.

6. An amusement device comprising, a plurality of independently operated swings, an inclined wall constituting a support disposed adjacent to said swings and in position to be reached by the feet of the occupants of said swings as the swings move back and forth, switches carried by the support and adapted to be operated by the feet of the swing occupants, and electric signals controlled by operation of said switches.

7. An amusement device comprising, a plurality of independently operated swings, a curved wall disposed adjacent to said swings and in position to be reached by the feet of the occupants of the swings as the swings are moved back and forth by the physical efforts of their occupants, switches mounted in the wall and arranged substantially flush with the surface thereof, signals, and electrical circuits connecting the signals and the switches and by which the signals are actuated when the switches are closed by the feet of the swing occupants.

8. An amusement device comprising a plurality of independently operated swings, a support adjacent to the swings, signals, a plurality of switches for each swing mounted in the support, and electrical circuits connecting the switches and signals whereby the signals will be operated by foot pressure imposed by the occupants of the

swings on the switches as the swings in their swinging movement carry the occupants to a position to operate the switches.

9. An amusement device comprising a plurality of independently operated swings, each of which is adapted to carry a passenger who propels the swing by his physical effort, a support disposed adjacent to the swings and over which the several swings are swung, a group of switches disposed on the support in front of each swing and arranged for successive foot-operation by the occupant of the swing, a visible signal electrically connected to each switch and arranged to operate when its switch is closed by the occupant of the swing moving adjacent to it, means for preventing actuation of the signals unless the same are operated in a predetermined sequence, an additional main signal electrically connected to the last signal in each group, and means by which the actuation of the main signal for one group will render the main signals for the other groups ineffective.

10. An amusement device comprising, a plurality of independently operated swings arranged in side-by-side relationship, a support over which each of the swings is swung by the physical efforts of only the passenger occupying the same, a group of switches on the support in front of each swing arranged transversely of the direction of movement of the swings, the switches in each group being adapted for operation by the passenger in the swing movable adjacent to the group, a visible signal electrically connected to and controlled by each of the switches, an additional main signal connected to and controlled by the last switch in each group, an audible signal also connected to and controlled by the last switch in each group, and means by which the actuation of the main signal and audible signal for one group will render similar signals for the other groups ineffective.

11. In an amusement device, a swing for carrying a passenger, a curved support adjacent to the path of movement of the swing, a number of switches mounted on the support, a number of signal lamps on the support, and electrical circuits between the lamps and the switches whereby a lamp will be illuminated by the pressure of the feet of the swing occupant on one of the switches when he is carried to a position by the swing to reach and operate said switch by foot pressure.

12. In an amusement device, a swing for carrying a passenger, a curved support adjacent to the path of movement of the swing, a group of switches mounted on the support, a number of signal lamps on the support, a winning signal on the support, electrical circuit between the switches and the lamps whereby a lamp will be illuminated by the pressure of the feet of the swing occupant on the switch to which said lamp is connected when the swing occupant is carried by the swing to a position to reach and operate said switch by foot pressure, means by which the switches are rendered ineffective unless the same are operated in a predetermined sequence, and an electrical circuit for operating the winning signal when the last switch in the group of switches is operated.

13. An amusement device comprising a series of independently operated swings mounted in a line and in side-by-side relation, an inclosed support toward which the swings are movable solely by efforts of the passenger in each swing, switches on the support over which the swing is swung, signals electrically connected to the switches whereby said signals are actuated by foot operation of the switches by the passenger of the swing, and means for requiring operation of said switches in a predetermined sequence to procure actuation of the signals.

WALTER LIEBRECHT.
